(57) **CLAIM**

The ornamental design for a solar-powered illuminated holiday sign, as shown and described.

DESCRIPTION

FIG. 1 is a front view of a solar-powered illuminated holiday sign, showing my new design;

FIG. 2 is a rear view thereof;

FIG. 3 is a left side view thereof with a right side view being a mirror image;

FIG. 4 is a top view thereof; and,

FIG. 5 is a bottom view thereof.

The broken line showing of inner features is for the purpose of illustrating surface features and forms no part of the claimed design.
